UNITED STATES PATENT OFFICE

2,566,507

CYLINDER SLEEVE PULLER

George M. Walraven and Raymond G. Knudsen,
Kenosha, Wis., assignors to Snap-On Tools
Corporation, Kenosha, Wis., a corporation of
Delaware

Application September 23, 1947, Serial No. 775,718

1 Claim. (Cl. 29—283)

1

This invention relates to pullers and more particularly to cylinder sleeve pullers, although certain features thereof may be employed with equal advantage for other purposes.

It contemplates more especially the provision of improved pullers involving adjustable tilttable engaging jaws that are effectively adapted to the pulling of cylinder sleeves.

Sleeve pullers are becoming increasingly popular owing to the fact that many internal combustion engines now resort to cylinder sleeves as liners rather than provide precision cylinders directly in the engine block. In rebuilding engines, it is only necessary to remove the cylinder sleeves that are press fitted in the cylinder bores and this is readily accomplished with a power puller that is effective in engaging the inner or lower peripheral edge of the sleeve prior to exerting an upward power or mechanical pull thereon.

One object of the present invention is to simplify the construction and improve the operation of devices of the character mentioned.

Another object is to provide an improved sleeve puller involving tilttable adjustable jaws.

Still another object is to provide an improved jaw member for engaging the lower peripheral edge of a cylinder sleeve prior to extending an upward or outward pull thereon.

A further object is to provide an adjustable sleeve engaging jaw that is tiltably connected to a shank for exerting a pull on a sleeve for removal from its bore in an internal combustion engine and the like.

A still further object is to provide an improved tilttable engaging jaw for sleeve pullers and the like.

Still a further object is to provide a tilttable member having spring impelled jaws thereon for engagement with the lower peripheral edge of a cylinder sleeve.

Other objects and advantages will appear from the following description of an illustrative embodiment of the present invention.

In the drawing:

Figure 1 is a side sectional view in elevation of a cylinder, cylinder sleeve, and a sleeve puller embodying features of the present invention.

Figure 2 is a front sectional view in elevation of the structure shown in Figure 1.

Figure 3 is a plan sectional view taken substantially along line III—III of Figure 2.

Figure 4 is a bottom plan view of the sleeve puller shown in the preceding figures.

Figure 5 is a sectional view taken substantially along line V—V of Figure 1.

2

Figure 6 is a sectional view taken substantially along line VI—VI of Figure 5.

The structure selected for illustration is not intended to serve as a limitation upon the scope or teachings of the invention, but is merely illustrative thereof. There may be considerable variations and adaptations of all or part of the teachings depending upon the dictates of commercial practice.

10 The present embodiment comprises a cylinder or engine block 10 having a cylinder bore 11 provided therein to receive a somewhat larger sleeve 12 that is press-fitted into the cylinder bore 11 to project therebelow as at 13. The lower peripheral edge 14 of the cylinder sleeve 12 is usually tapered or chamfered to provide a more or less sharp circumferential edge 15.

15 The problem of removing the cylinder sleeve 12 from the cylinder 11 is rendered rather simple by utilizing a puller that effectively engages the lower peripheral edge 15 of the sleeve 12 and exerting an upward or outward pull thereon by any suitable actuator such as a mechanical screw member or hydraulic ram of a portable type. The specific type of actuator may be varied within a wide range depending upon the dictates of commercial practice. The actuator is engageable with or constitutes a part of a threaded stud or shank 16 which engages a correspondingly threaded recess or bore 17 provided in a coupler 18 comprising the extremity of a link member 19. The link member 19 terminates, in this instance, in an enlarged circular boss 20 which is transversely bored to receive a threaded pivot pin 21 having a polygonal recess 22 provided in an enlarged head 23 thereof.

20 The pivot 21 projects transversely through spaced furcations 24—25 which are fitted to receive the boss 20 therebetween. The pivot stud 21 threadededly engages the furcations 24—25 to pivotally support a substantially rectangular jaw body 26 formed integral with the furcations 24—25. The jaw body 26 comprises a tangential diametrical portion of an otherwise circular member and has diametrically disposed jaw receiving guides 27—28 provided therein to receive opposing jaw members 29—30 that are radially slidable therein. The limit of radial slidable displacement of the jaws 29—30 within the guides 27—28, is determined by pins 31—32 anchored in the upper surface of the jaws 29—30 for registry with confronting slots 33—34 provided in the jaw body 26. The jaws 29—30 are normally urged 25 outwardly by means of coil springs 35—36 which

are disposed within the jaw body 26 to engage a central boss 37 formed therein.

The jaws 29-30 are free to move outwardly to their extreme position under the urge of the springs 35-36 or held in any pre-determined adjusted position by means of a lower jaw plate 38. The lower jaw plate 38 has an axially tapered aperture 39 therein to receive a correspondingly tapered head 40 of a threaded stud 41 that engages a correspondingly threaded bore 42 provided within the boss 37 of the jaw body 26. A hexagonal or other polygonal recess 43 is provided in the stud head 40 to enable the tightening or loosening thereof with a suitable key or wrench. The stud 41 is adjusted to tighten or loosen the jaw plate 38 to preset the extent of projection of the radial jaws 29-30. The jaws 29-30 have inwardly disposed offsets 44-45 which present outwardly disposed shoulders 46-47 that are capable of engaging a peripheral lower edge 15 of the cylinder sleeve 12.

The offsets 44-45 approach the internal diameter of the cylinder sleeve 12 so that the shoulders 46-47 will extend beyond the lower peripheral edge 15 of the sleeve 12. With this arrangement the jaw body 26 is pivoted at an angle relative to the elongated member or shank 19 during the insertion thereof for downward displacement through the cylinder sleeve 12 until the jaw body 26 with the jaws 29-30 are displaced below the peripheral sleeve edge 15. Thereupon, the jaw body 26 will assume a horizontal position so that the jaws 29-30 with their shoulders 46-47 can engage the lowermost peripheral sleeve edge 15. As upward pull is thereafter exerted on the shank member 19 by an actuator of any suitable type which is attached to the threaded shank 16 to exert a force relative to the cylinder block 10 for effecting the removal of the sleeve 12 from the cylinder bore 11.

It should be observed that the jaw body 26 need not be tiltable, since the jaws 29-30 are spring urged outwards without presetting them so that a rigidly attached jaw body 26 can be displaced downwardly through the cylinder sleeve 12 as shown in dotted outline in Figure 2. When the jaws 29-30 reach a position beneath the

lower peripheral sleeve edge 15, they are displaced further outwardly by the springs 35-36 to engage the lower peripheral sleeve edge 15. Thereafter, the actuator can be utilized to effect the upper displacement of the sleeve 12 relative to the cylinder bore 11 to effect a removal thereof.

While we have illustrated and described a preferred embodiment of this invention, it must be understood that the invention is capable of considerable variation and modification without departing from the spirit of the invention. We, therefore, do not wish to be limited to the precise details of construction set forth, but desire to avail ourselves of such variations and modifications as come within the scope of the appended claim.

We claim:

A sleeve pulling device comprising an elongated shank, a jaw body tiltably associated with said shank for enabling insertion through a sleeve, opposed jaws slidably disposed in said jaw body, spring means for normally urging said jaws outwardly to engage the lower peripheral edge of a sleeve, means for limiting the extension of said jaws, an adjustable jaw engaging plate, and means including said adjustable jaw engaging plate for maintaining said jaws in a preset extent of adjustment, said jaw body being a tangential diametrical portion of an otherwise circular member to permit insertion in a sleeve for jaw engagement thereunder for the purpose set forth.
